Matthew L. Bycer(57) **CLAIM**

The ornamental design for a wraparound step cover as shown and described.

DESCRIPTION

FIG. 1 illustrates a top perspective view of a wraparound step cover;

FIG. 2 illustrates a top plan view thereof;

FIG. 3 illustrates a bottom plan view thereof;

FIG. 4 illustrates a right side view thereof;

FIG. 5 illustrates a left side view thereof;

FIG. 6 illustrates a front view thereof; and,

FIG. 7 illustrates a rear view thereof.

The drawings set forth a unique design for a wraparound step cover.

The broken lines and surface textures shown in the drawings represent portions of the wraparound step cover that form no part of the claimed design.
